UNITED STATES PATENT OFFICE.

JULIUS J. PAULE, OF NORTH BALTIMORE, OHIO.

WRENCH.

Application filed December 16, 1925. Serial No. 75,727.

This invention relates to new and useful improvements in pipe wrenches and has for its principal object to provide a tool of this character which may be quickly adjusted to 5 the desired size and with the minimum effort on the part of the operator.

With the foregoing and other objects in view that will readily appear as the nature of my invention is better understood, the 10 same consists in the novel features of construction, combination and arrangement of parts illustrated in the accompanying drawings and more particularly pointed out in the appended claim.

15 In the accompanying drawings, which are for illustrative purposes only and are therefore not drawn to scale:

Figure 1 is a side elevation of an adjustable pipe wrench embodying my improvements.

20 Figure 2 is a longitudinal section.

Figure 3 is a vertical transverse section, and

25 Figure 4 is a detail perspective view of the front end of the handle and stationary jaw.

Referring to the drawings for a more particular description of my invention and in which drawings like parts are designated by 30 like reference characters throughout the several views, the numeral 1 designates the handle of the wrench, provided at its inner or forward end with a stationary jaw 2 formed on its outer end or edge with the 35 downwardly inclined teeth 3.

The numeral 4 represents the movable member of the wrench, consisting of the straight elongated shank 5 provided at its forward end with the movable jaw 6 formed 40 on its inner edge or wall with the upwardly inclined teeth 7. The handle 1 of the wrench and shank 5 of the movable member 4 are held together by the yoke 8, and the latter formed at the top with spaced lugs 45 9 between which is mounted by means of the horizontal bearing pin 10, the worm 11, whose teeth are adapted to mesh with the rack teeth 12 formed on the upper edge of said movable member 4. The yoke is held 50 in operative position by the cross pin 13 carried by the handle 2 with its ends extending into vertical elongated slots 14 formed in opposite sides 15 of the yoke. The yoke is normally held in lowered position

and the worm 11 in engaged relation with 55 the rack 12 by the resilient elements 16 mounted on the bearing 17, but said yoke may be elevated to release the worm from the rack by grasping the wrench in one hand and pressing against the bottom of the yoke 60 with the thumb. An approximate adjustment of the movable jaw may then be easily and quickly made and the worm used for finer adjustments when the pressure on the yoke is released.

65 The front end of the handle 1 is provided with a central longitudinal slot or recess 18 and the stationary jaw 3 formed with three longitudinal parallel transversely spaced tongues 19 and 20. When the stationary jaw 70 is in place, the central tongue 19 fits in the slot or recess 18 of the handle and the outer tongues 20 embrace or fit against opposite side faces of the front end of the handle and co-operate with the transverse ribs 21 75 in guiding and preventing any lost motion of the yoke 8. The stationary jaw 3 is secured or fastened to the front end of the handle by the transverse pins or rivets 22.

80 My device is simple and economical in construction and highly efficient and practical in operation.

From the foregoing description taken in connection with the drawings, it is thought that the construction, operation and advantages 85 of my invention will be readily understood without requiring a more extended explanation.

Various changes in the form, proportions and minor details of construction may be 90 resorted to without departing from the principle or sacrificing any of the advantages of my invention as defined in the appended claim.

Having described my invention, what I 95 claim as new and desire to secure by Letters Patent, is:—

In an adjustable pipe wrench, a handle provided at one end with a stationary jaw, a movable member comprising a straight 100 elongated shank and a jaw co-operating with said stationary jaw, there being oppositely inclined teeth formed on said jaws, a transversely movable yoke fitting over the handle and shank of the movable member, there 105 being a rack formed on the upper edge of said shank, a worm carried by the yoke and co-operating with the rack in adjusting the

movable jaw, resilient means for normally holding the yoke in operative position and the worm in engagement with the rack, a pin and slot connection between the yoke and handle and transverse tongues or ribs provided on the stationary jaw and handle and engaging opposite side edges of the yoke,

said tongues or ribs co-operating with the pin and slot connection in guiding and preventing lost motion of the yoke.

In testimony whereof he affixes his signature.

JULIUS J. PAULE.
